OF 19,914

UNITED STATES PATENT OFFICE.

FRANCIS RITCHIE, OF TROY, NEW YORK, ASSIGNOR TO ISAAC A. SHEPPARD, FRANKLIN L. SHEPPARD, AND HOWARD R. SHEPPARD, ALL OF PHILADELPHIA, PENNSYLVANIA.

DESIGN FOR A HEATING-STOVE.

SPECIFICATION forming part of Design No. 19,914, dated June 17, 1890.

Application filed May 6, 1890. Serial No. 350,797. Term of patent 7 years.

To all whom it may concern:

Be it known that I, FRANCIS RITCHIE, a citizen of the United States, and a resident of Troy, New York, have invented a new and 5 Original Design for a Stove, of which the following is a specification.

My design for a stove is clearly shown in the annexed photographic representation. The predominating feature of the design is 10 the shell-like ornamentation on both the base and body of the stove. Each corner of the base A is rounded, and at the corner is the representation of a neptune's box-shell, and at the center is also the representation of the 15 same shell, and extending along the base is a shell-like scroll. The base of the ash-pit section B is likewise rounded at the corners, having thereon the representation of a neptune's box-shell, the base of the shell being down, 20 while the base of the shell represented in the base-section is inverted. The shell on the base of the ash-pit section is surrounded by a ring terminating at the base of the shell. The ornamentation of the ash-pit door is in 25 the form of a shell-like scroll extending from the two lower corners at an angle toward the middle and separating into return-scrolls. The design of the doors D and E of the combustion-chamber section are in keeping with the 30 other designs, the doors being barred, and projecting from a medallion in the center are four sprays, which cross the barred doors in

the shape of foliated scrolls. The dome of the stove has rounded corners with shell-like designs in each corner, and the plates of the 35 dome are ornamented with medallions surrounded by shell-like scrolls, and the crown of the dome is also ornamented with shell-like scrolls in keeping with the rest of the design. The foot-rests G at each side of the ash-pit 40 section are ornamented at the ends with ornamental representations representing conch-shells, and the cross-piece is also ornamented in keeping with the rest of the design.

I claim—

- 45 1. The design for a stove, as herein set forth, and as shown in the accompanying photographic representation.
2. In the design for a stove, the design for a door of a stove, the shell-like scrolls extending from the two lower corners at an angle toward the middle and separating into return-scrolls, as herein shown and described.
- 50 3. In the design for a stove, the design for the ends of the foot-rests of a stove, as herein shown and described.

55 In testimony whereof I have signed my name to this specification in the presence of two subscribing witnesses.

FRANCIS RITCHIE.

Witnesses:

CHESTER BASCOM,
CHARLES H. BENEDICT.
